UNITED STATES PATENT OFFICE.

LOUIS MARX, OF BROOKLYN, NEW YORK.

MECHANICALLY-OPERATED TOY.

Application filed June 9, 1926. Serial No. 114,657.

This invention relates to a toy or amusement device, and more particularly to a mechanically operated toy; and has special reference to the provision of an improved 5 roundabout toy or amusement device.

One of the principal objects of my present invention comprehends the provision of an improved roundabout toy or amusement device in which a figure such as a 10 vehicle or the like is caused to rotate in cycles about a platform with means provided for automatically stopping the rotation of said vehicle after the vehicle has moved uninterruptedly a plurality of cycles 15 or revolutions about the platform, the automatic stop means being constructed to permit the vehicle to cyclically move about the platform a predetermined number of times before bringing the same to a stop.

20 A further prime object of my present invention comprehends the provision of an amusement device or toy of the character referred to in which is provided a figure having a signal indicating arm movable between "go" and "stop" positions with 25 mechanism for automatically moving the signal indicating arm to the "stop" indicating position after the rotatable vehicle has moved a predetermined plurality of cycles 30 or revolutions about the platform; and the further provision of an improved roundabout toy of this nature in which the "go-stop" indicating means is associated with the automatic "stop" mechanism to produce 35 a cooperative action between the same so as to effect a stopping of the rotatable vehicle simultaneously with an operation of the indicating means to the "stop" position.

A still further object of my present invention comprehends the provision of a roundabout toy in which the "go-stop" indicating means and the automatic stop for the vehicle are operated by the movement of the vehicle, all the parts being operated 45 by a single motor mechanism.

A still further important object of the invention resides in the provision of a roundabout toy made to simulate the conducting of street traffic, the "go-stop" indicating 50 means comprising a "go-stop" sign and a traffic officer associated therewith, both being operated between "go" and "stop" positions, the operation of the "go-stop" sign and the simulated traffic officer being effected 55 simultaneously with the operation of the automatic stop mechanism for the vehicle.

Ancillary objects of the invention are the provision of a toy designed to perform the cooperative functions aforesaid with few operating parts constructed so as to permit 60 the toy to be manufactured with ease and at low cost.

To the accomplishment of the foregoing and such other objects as will hereinafter appear, my invention consists in the elements 65 and their relation one to the other, as hereinafter more particularly described and sought to be defined in the claims; reference being had to the accompanying drawings which show the preferred embodiment of my 70 invention, and in which:

Fig. 1 is a perspective view of the roundabout toy embodying the principles of my present invention,

Fig. 2 is a fragmentary enlarged bottom 75 plan view thereof,

Fig. 3 is a view similar to that shown in Fig. 2 with the parts shown in a different position,

Fig. 4 is a fragmentary cross-sectional 80 view taken on the line 4-4, Fig. 2 with the parts shown in an advanced position, and

Fig. 5 is a fragmentary cross-sectional view taken on the line 5-5, Fig. 2.

Referring now more in detail to the drawings, the toy or roundabout device of my invention comprises generically a platform or support generally designated as A, a movable figure B movable cyclically around the platform A and operated by a motor generally designated by the motor housing C on the platform A, the cyclic rotation of the figure B being controlled by an automatic stop mechanism generally designated as D, which stop mechanism operates to automatically bring the figure B to a halt simultaneously with the operation of "go-stop" indicating means generally designated as E.

The platform or support A is preferably of the type in which an annular track is provided for the movement of the movable figure and said platform comprises a central disk section 10, an annular section 11, the said annular section being spaced from the central disk section 10 so as to provide or define an annular track 12 in which the figure B rotates. The annular section 11 is provided with a depending skirt portion 13 which forms the support for the toy and the disk section 10 is supported on the annular section 11 by means of a plurality of arches 14, 14

(four in number) which may be given any desired contour or design. The disk section 10 supports the operating and operated parts of the toy, as will be seen more in detail hereinafter.

The movable figure B may be made to simulate a figure or animal, and in the construction exemplified in the drawings the figure is shown in the form of an automotive vehicle which in its simplest form may be made of suitably embellished sheet material cut and bent into the desired configuration.

The vehicle figure B is cyclically rotated in the annular track 12 by means of a motor which is supported on the disk section 10 of the platform, which motor (not shown) is housed in the motor casing C through which projects a winding key 15 adapted to be grasped for winding the motor, the said motor including a driven shaft 16 which extends to the underneath side of the disk section 10 of the platform and which is preferably integral with a radially extending connecting rod 17 which is provided at its front end with an upwardly bent portion 18 fixed to the vehicle B. From this construction it will be apparent that when the motor is energized by the winding key 15 the operating shaft 16 thereof will be actuated to move the vehicle B cyclically in its track.

The automatic stop mechanism D heretofore referred to is constructed to bring the vehicle to a halt after the same has moved uninterruptedly a plurality of cycles or revolutions about the platform. In the construction exemplified in the drawings, this automatic stop mechanism D comprises a pair of cooperable stop elements 19 and 20, the element 19 being actuated by the rotation of the vehicle B during each revolution thereof in a manner to be described presently so that the same is advanced and brought into engagement with the stop element 20, such engagement bringing the vehicle to a halt.

A desideratum of the invention centers about the provision of a stop mechanism which permits unhindered rotation of the vehicle a predetermined plurality of times about the platform before the same is brought to a stop; and to accomplish the desired result the stop element 19 of the stop mechanism is operated so that the same is brought into engagement with the stop element 20 only after the vehicle has moved a plurality of revolutions. To effect this result, there is provided a rotatable element 21 having a predetermined number, such as four, pins 22, 22 thereon, which project in the path of movement of a finger 23 fixed to the connecting rod 17, the construction being such that during each revolution of the vehicle and the rod 17 a pin 22 is engaged by the finger 23 to move the rotatable element 21 a part such as a quarter of a turn in the

direction shown by the arrow in Fig. 2 of the drawings. The stop element 19 is fixed to the rotatable element 21 and therefore partakes of its movement so that the stop element 19 is brought into position (Fig. 3 of the drawings) to engage the stop element 20 only after a plurality of rotations of the vehicle have been effected. When the stop elements engagingly coat as shown in Fig. 3 of the drawings, one of the pins 22 is still in engagement with the finger 23 so that the movement of the connecting rod is checked and the vehicle is brought to a halt. At other times the rotatable element 21 actuated by the rotation of the rod 17 is moved to a position to free the finger 23, thus permitting the continued or unimpeded rotation of the vehicle.

The signal indicating means D comprises a pair of figures on the platform 10 operated in unison with the automatic stop mechanism to produce signal stop indications of the figures. These figures preferably comprise a simulated traffic officer 24 and a movable "go-stop" sign 25, the traffic officer having a pivoted arm 26 movable from the full "go" position to the dotted line "stop" indicating position shown in Fig. 1 of the drawings. The "go-stop" sign 25 is provided with signal indicating arms 27, 27 also movable by the rotation of the "go-stop" sign between "go" and "stop" positions. Both of the figures 24 and 25 are operated by the rotation of the vehicle B in unison with the operation of the automatic stop mechanism.

For operating the traffic officer figure, there is provided a rod 28 which is connected at its upper end to a crank shaft 29 concealed by the body of the figure, to which shaft the arm 26 is fixed, the lower end of the connecting rod 28 extending beneath the platform 10 in position to be engaged by an arm 30 pivoted as at 31 to the platform 10. The arm 30 lies in the path of movement of the stop element 19 as shown in Figs. 3 and 4 of the drawings and is arranged to be engaged thereby, as shown in Fig. 3 of the drawings, to elevate the same and to cause the rod 28 to ascend, which action operates the policeman's arm 26 to the "stop" indicating position. With the parts as shown in Fig. 3 of the drawings, the vehicle is at a halt and the policeman's arm continues to indicate "stop". When the parts are manually released, as will be described hereinafter, the stop element 19 is moved to release the arm 30 and the weight of the parts then permits the policeman's arm 26 to drop to the "go" position.

The "go-stop" sign 25 is actuated in the construction exemplified by the engagement between the stop elements 19 and 20. The "go-stop" sign is provided with a post 32 movable in a bearing 33, the lower end of said post being fixedly attached to a link

34, the outer end of which link is pivotally connected, as at 35, to the stop element 20. The stop element 20 is movable by the engagement of the stop element 19 from the 5 normal position shown in Fig. 2, held in such normal position by means of a spring 36, to an actuated spring-tensioned position shown in Fig. 3; and when so moved the "go-stop" sign 25 is rotated a quarter of a 10 turn in the direction shown by the arrows in Figs. 2 and 3 of the drawings, the sign being moved from the "go" to the "stop" indicating position. It will be understood that the 15 spring 36 is a light leaf spring sufficient in power only to return the parts to normal position, the strength of which is overbalanced by the more powerful spring of the operating motor for the toy.

With the above-recited construction it 20 will be apparent that after a plurality of revolutions of the vehicle have been effected, which is predetermined by the design of the rotatable element 21, the vehicle is brought to a halt by the engagement between the 25 stop elements 19 and 20, the arm 26 of the traffic officer figure is moved to the "stop" position by the engagement of the stop element 19 with the arm 30, and the "go-stop" sign 25 is moved from the "go" to the 30 "stop" position by the actuation of the stop element 20 when engaged by the stop element 19.

To release the parts to permit continued activity of the toy until the operating motor 35 is unwound, it is only necessary to manually move one of the parts such as the "go-stop" sign a partial revolution in the direction shown by the arrows in Fig. 3 of the drawings. By so doing the stop element 20 is 40 moved from the full-line to the dotted line position shown in Fig. 3 of the drawings, such motion permitting the forward end of the stop element 20 to seat in a channel 37 provided in the platform 10, as shown particularly in Fig. 5 of the drawings. The 45 parts are so constructed that the element 20 is normally urged against the platform, this being assisted by the guide yoke 38, and when moved to the dotted line position it 50 seats in the channel 37 and is thus moved upwardly out of the path of the stop element 19, the downwardly projecting finger 20' of the stop element being also bevelled to facilitate the escape of the stop element 55 19. When the stop element 19 passes or escapes the stop element 20, the vehicle B continues its rotation and the remaining parts of the toy are moved to their normal positions. Thus the weight of the arm 30 60 assisted by the weight of the rod 28 causes the traffic officer figure to move to the normal position and the spring 36 causes the "go-stop" sign to move to the "go" position, the stop element 20 being simultaneously moved 65 to the position shown in Fig. 2 of the draw-

ings ready for the next engagement with the stop element 19.

The use and operation of my roundabout toy and the many advantages thereof will in the main be fully apparent from the above 70 detailed description thereof. It will be further apparent that while I have shown and described my invention in the preferred form, that many changes and modifications may be made in the structure disclosed without departing from the spirit of the invention, defined in the following claims.

I claim:

1. In an amusement device, a platform, a motor on said platform, a figure rotatable 80 cylindrically around said platform and connected to and operated by said motor, and an automatic stop mechanism for the rotatable figure, said stop mechanism comprising means operable to automatically stop the 85 rotation of said figure when the same has moved uninterruptedly a plurality of cycles or revolutions about said platform.

2. In an amusement device, a platform, a motor on said platform, a figure rotatable 90 cylindrically around said platform and connected to and operated by said motor, and an automatic stop mechanism for the rotatable figure, said stop mechanism comprising 95 means operable by the movement of said figure to automatically stop the rotation of said figure when the same has moved uninterruptedly a plurality of cycles or revolutions about said platform.

3. In a roundabout toy, a central platform, 100 an annular member spaced from said platform, the space between the member and platform defining an annular track, a motor on said platform, a toy vehicle movable cyclically in said annular track and connected 105 to and operated by said motor, and an automatic stop mechanism for the toy vehicle, said stop mechanism comprising means operable to automatically stop the movement 110 of said toy vehicle when the same has moved unimpededly a plurality of cycles or revolutions in said annular track.

4. In an amusement device, a platform, a motor on said platform, a figure rotatable 115 cyclically around said platform, means connecting said figure with said motor, and an automatic stop mechanism for the rotatable figure, said stop mechanism comprising a pair of cooperable stop elements, one of the stop elements being actuated by said connecting means during each revolution of said figure to advance the same and being brought into stop engagement with the other of said stop elements after said figure has moved uninterruptedly a plurality of cycles or revolutions about said platform.

5. In an amusement device, a platform, a motor on said platform, a figure rotatable 120 cyclically around said platform and connected to and operated by said motor, a fig-

- ure on said platform having a signal indicating arm movable between "stop" and "go" positions, and mechanism for automatically moving the signal indicating arm to the "stop" indicating position, said mechanism comprising means operable only after the rotatable figure has moved a plurality of cycles or revolutions about said platform.
6. In an amusement device, a platform, a motor on said platform, a figure rotatable cyclically around said platform and connected to and operated by said motor, a figure on said platform having a signal indicating arm movable between "stop" and "go" positions, and mechanism for automatically moving the signal indicating arm to the "stop" indicating position, said mechanism comprising means operable by the movement of said rotatable figure and only after the rotatable figure has moved a plurality of cycles or revolutions about said platform.
7. In a roundabout toy, a central platform, an annular member spaced from said platform, the space between the member and platform defining an annular track, a motor on said platform, a toy vehicle movable cyclically in said annular track and connected to and operated by said motor, a figure on said platform having a signal indicating arm movable between "stop" and "go" position, and mechanism for automatically moving the signal indicating arm to the "stop" indicating position, said mechanism comprising means operable only after the toy vehicle has moved a plurality of cycles or revolutions about said platform.
8. In an amusement device, a platform, a motor on said platform, a figure rotatable cyclically around said platform and connected to and operated by said motor, an automatic stop mechanism for the rotatable figure, a figure on said platform having a signal indicating arm movable between "stop" and "go" positions, mechanism for automatically moving the signal indicating arm to the "stop" indicating position and means for operating both of said mechanisms to "stop" indicating position and figure stopping positions when the rotatable figure has moved uninterruptedly a plurality of cycles or revolutions about said platform.
9. In an amusement device, a platform, a motor on said platform, a figure rotatable cyclically around said platform and connected to and operated by said motor, an automatic stop mechanism for the rotatable figure, a figure on said platform having a signal indicating arm movable between "stop" and "go" positions, mechanism for automatically moving the signal indicating arm to the "stop" indicating position and means operated by the movement of said rotatable figure for operating both of said mechanisms to "stop" indicating and figure stopping positions when the rotatable figure has moved uninterruptedly a plurality of cycles or revolutions about said platform.
10. In an amusement device, a platform, a motor on said platform, a figure rotatable cyclically around said platform, means connecting said figure with said motor, and an automatic stop mechanism for the rotatable figure, said stop mechanism comprising a pair of cooperable stop elements, one of the stop elements being actuated by said connecting means during each revolution of said figure to advance the same and being brought into stop engagement with the other of said stop elements after said figure has moved uninterruptedly a plurality of cycles or revolutions about said platform, a figure on said platform having a signal indicating arm movable between "stop" and "go" positions and means for moving the signal indicating arm to the "stop" position when the said stop elements are brought into said stop engagement.
11. In an amusement device, a platform, a motor on said platform, a toy vehicle rotatable cyclically around said platform and connected to and operated by said motor, a policeman figure on said platform provided with a movable arm, a "go-stop" sign provided with a movable "go-stop" indicating arm and means operated by the rotation of said toy vehicle for moving the arm of the policeman figure and the arm of the "go-stop" sign to the "stop" indicating positions.
12. In an amusement device, a platform, a motor on said platform, a toy vehicle rotatable cyclically around said platform and connected to and operated by said motor, a policeman figure on said platform provided with a movable arm, a "go-stop" sign provided with a movable "go-stop" indicating arm and means operated by the rotation of said toy vehicle for automatically moving the arm of the policeman figure and the arm of the "go-stop" sign to the "stop" indicating positions, said means including mechanism operable only after the toy vehicle has moved a plurality of cycles or revolutions about said platform.
13. In a roundabout toy, a central platform, an annular member spaced from said platform, the space between the member and platform defining an annular track, a motor on said platform, a toy vehicle movable cyclically in said annular track and connected to and operated by said motor, a policeman figure on said platform provided with a movable arm, a "go-stop" sign provided with a movable "go-stop" indicating arm and means operated by the rotation of said toy vehicle for moving the arm of the policeman figure and the arm of the "go-stop" sign to the "stop" indicating positions.
14. In an amusement device, a platform, a motor on said platform, a toy vehicle rotat-

- able cyclically around said platform and connected to and operated by said motor, an automatic stop mechanism for the vehicle, a policeman figure on said platform provided with a movable arm, a "go-stop" sign provided with a movable "go-stop" indicating arm and means operable only after the vehicle has moved a plurality of cycles or revolutions about said platform for operating the stop mechanism to stop the vehicle and for simultaneously operating the arm of the policeman figure and the arm of the "go-stop" sign to the "stop" indicating positions.
5. with a movable arm, a "go-stop" sign provided with a movable "go-stop" indicating arm and means operable only after the vehicle has moved a plurality of cycles or revolutions about said platform for operating the stop mechanism to stop the vehicle and for simultaneously operating the arm of the policeman figure and the arm of the "go-stop" sign to the "stop" indicating positions.
10. the stop mechanism to stop the vehicle and for simultaneously operating the arm of the policeman figure and the arm of the "go-stop" sign to the "stop" indicating positions.
15. In an amusement device, a platform, a motor on said platform, a toy vehicle rotatable cyclically around said platform and connected to and operated by said motor, an
- automatic stop mechanism for the vehicle, a policeman figure on said platform provided with a movable arm, a "go-stop" sign provided with a movable "go-stop" indicating arm and means operable only after the vehicle has moved a plurality of cycles or revolutions about said platform for operating the stop mechanism to stop the vehicle and for simultaneously operating the arm of the policeman figure and the arm of the "go-stop" sign to the "stop" indicating positions, said means comprising mechanism operable by the rotation of the vehicle.
20. 25. 30.

Signed at New York city, in the county of New York and State of New York this 4th day of June A. D. 1926.

LOUIS MARX.
